UNITED STATES PATENT OFFICE

EARL E. EICKMEYER, OF DAYTON, OHIO, ASSIGNOR TO THE DAYTON PUMP & MFG. COMPANY, OF DAYTON, OHIO, A CORPORATION OF OHIO

GASOLINE PUMP

Application filed June 23, 1927. Serial No. 200,785.

My invention relates to gasoline pumps and in particular to sight glasses therefor.

It is the object of my invention to provide a visible float mechanism for use as a sight glass in which the level of the gasoline at the top thereof is always visibly indicated to the purchaser, so that the top is not hidden by the dome or cap of such visible sight glasses heretofore known in the art.

10 Heretofore, the chamber consisting of the glass cylinder, the metal retaining cage and the dome has been filled with gasoline up to the level where the gas would run out the opening in the dome into the hose but this 15 left the level of the gasoline at a point where the purchaser could not see it so that it would be possible for an unscrupulous salesman to cheat the purchaser out of the amount of gasoline due him. This would amount to 20 several inches of gasoline each time and a continuous cheating to this extent would become a considerable amount during the course of a day's business.

It is my object to provide means by which 25 the gasoline will be evacuated from the sight glass down to a point where the top of the gasoline will be always visible.

Referring to the drawings:

Figure 1 is a side elevation of my device; 30 Figure 2 is a section on the line 2—2 thereof;

Figure 3 is a top plan view.

Referring to the drawings in detail, 1 is a supply pipe threaded at 2 into the base 35 3 of a cage having spaced projecting arms 4 joined together by a ring or cap 5 at the top thereof. A glass cylinder 6 is mounted within the cage so that the gasoline therein may be observed and so that the rotation of the 40 spinner 7 may be observed, which spinner indicates the flow of the gasoline.

It is my object to bring the level of the gasoline to the line marked 8 which is below the bottom of the top ring 5, so that the gas 45 will always be seen to terminate at a point below the lower edge of this top ring.

The glass cylinder has mounted thereon a dome member consisting of a flange 9 carrying a gasket 10 and upright dome wall 11 50 forming part of the dome 12. This dome 12

is provided with a side aperture 13 to which is connected the hose 14. This hose extends down from the dome, and has a siphon action in removing the contents of the cylinder. This siphon action ceases when the contents 55 reach a certain level determined by the admission of air into the cylinders and around the edge of the skirt 15. Within the dome there is a depending inwardly projected open mouthed skirt 15, the lower edge of which designated 16 coincides with the line 8 and is visible through the glass 6 at a point below the bottom edge of the ring 5.

This skirt 15 is spaced from the wall 11 to form a space 17 which communicates with an air release valve 18 having a pasageway 19 terminating in a valve seat 20. Communicating with the valve seat 20 is a port 21 communicating with outside air. The valve seat is adapted to receive a ball 22 which 70 closes the port 21. This ball operates by gravity.

The top of the dome carries a sign 23 on the bracket 24. The dome itself is attached to the cage by the bolts 25, so that a strong 75 integral housing is provided, the strain of the hose being communicated through the metal cage to the supporting pipe 1 without imparting any crushing strains upon the glass 6.

If desired, a red line can be drawn across the glass corresponding to the line 8 in order to indicate to the purchaser where the level of the gasoline should be within the visible sight glass.

Method of operation.—In operation when the gasoline flows out of the hose, it will continue to flow even after the gasoline descends below the lower edge of the opening 13 communicating with the hose 14 due to the siphoning action facilitated by the downwardly extending skirt 15. This siphoning action, due to the suction created, will cause the ball 22 to lift and air be sucked into the space 17. The siphoning action will be 90 broken off when the gas level reaches the edge 16 of the skirt 15 because at that point the air in the pasageway 17 can flow around the edge 16 and the siphoning action will be 95 terminated.

It will be understood that I desire to comprehend within my invention such modifications as may be necessary to adapt it to varying conditions and uses.

Having thus fully described my invention, what I claim as new and desire to secure by Letters Patent, is:

1. In a sight glass mechanism, the combination of a gasoline supply and exit line, a sight glass, a dome member mounted on said sight glass, and means on the dome forming an air passage and extending to a point within said sight glass which is visible therethrough to admit air and said dome having means near the top thereof for connection to the exit line.

2. In a sight glass mechanism, the combination of an inlet pipe, a cage having apertures therein, a sight glass carried in said cage, a dome mounted on said sight glass having an exit passageway above the sight glass, a siphon hose connected to said passageway and an inwardly extending downwardly projected skirt carried by said dome spaced from one wall thereof to form an air chamber, the lower end of said skirt being visible through said sight glass, and means for controlling the communication of said air chamber with the outside atmosphere consisting of a valve passageway having a valve seat controlling an atmospheric port, and a ball mounted in said passageway adapted to rest on said seat and close said port whereby the siphoning action of the fluid making its departure through the hose will draw out the fluid from the sight glass and draw in the air through the said port in which the air chamber handling the fluid reaches the bottom of said skirt whereupon the air in said air passageway will break the siphoning action and the fluid will cease to flow.

3. In a sight glass mechanism, the combination of an inlet pipe, a cage having apertures therein, a sight glass carried in said cage, a dome mounted on said sight glass having an exit passageway above the sight glass, a siphon hose connected to said passageway and an inwardly extending downwardly projected skirt carried by said dome spaced from one wall thereof to form an air chamber, the lower end of said skirt being visible through said sight glass, and means for controlling the communication of said air chamber with the outside atmosphere consisting of a valve passageway having a valve seat controlling an atmospheric port, and a ball mounted in said passageway adapted to rest on said seat and close said port whereby the siphoning action of the fluid making its departure through the hose will draw out the fluid from the sight glass and draw in the air through the said port in which the air chamber handling the fluid reaches the bottom of the skirt whereupon the air in said air passageway will break the siphoning action and the fluid will cease

to flow, and spinner mechanism suspended from said dome for indicating the flow of fluid while said flow is taking place through the sight glass mechanism.

4. In a sight glass mechanism, the combination of a supply line, a siphon and exit line, a sight glass, a dome member mounted on said sight glass having a part extending to a point within said sight glass which is visible therethrough, said dome having means near the top thereof for connection to said exit line, said part forming an air chamber from the top of the dome to the bottom of the portion of the dome which extends into the sight glass, and means for permitting the entrance of air into said air chamber when the siphoning action is taking place.

5. In a sight glass mechanism, the combination of a gasoline supply line, a siphon exit line, a sight glass, a dome member mounted on said sight glass having a part extending to a point within said sight glass which is visible therethrough, and having means near the top thereof for connection to said exit and siphon line, said part of said dome forming an air chamber from the top of the dome to the bottom of that portion of the dome which extends into the sight glass, and means for permitting the entrance of air into said air chamber when the siphoning action is taking place and to prevent siphoning when the gasoline reaches a certain level.

In testimony whereof, I affix my signature.

EARL E. EICKMEYER.
